CLAIM

The ornamental design for a wireless charging transmitter, as shown and described.

DESCRIPTION

FIG. 1 is a front view of a wireless charging transmitter; FIG. 2 is a back view of the wireless charging transmitter; FIG. 3 is a left side view of the wireless charging transmitter; FIG. 4 is a right side view of the wireless charging transmitter;

FIG. 5 is a top plan view of the wireless charging transmitter;

FIG. 6 is a bottom plan view of the wireless charging transmitter;

FIG. 7 is a front perspective view of the wireless charging transmitter; and,

FIG. 8 is a back perspective view of the wireless charging transmitter.
